Primary Examiner — Ricky Pham(74) *Attorney, Agent, or Firm* — Notaro, Michalos & Zaccaria P.C.(57) **CLAIM**

The ornamental design for a small knife, as shown and described.

DESCRIPTION

FIG. 1 is a left side elevational view of a small knife showing my design therefor;

FIG. 2 is a top plan view thereof;

FIG. 3 is a bottom plan view thereof;

FIG. 4 is a front view thereof;

FIG. 5 is a back view thereof; and,

FIG. 6 is a right side elevational view thereof.

The handle shown in broken lines forms no part of the design.

1 Claim, 5 Drawing Sheets(56)
